UNITED STATES PATENT OFFICE.

LUIGI GALLINGANI, OF GENOA, ITALY.

HULL FOR VESSELS IN ARMED CONCRETE.

1,299,699.

Specification of Letters Patent.

Patented Apr. 8, 1919.

Application filed August 16, 1918. Serial No. 250,249.

To all whom it may concern:

Be it known that I, LUIGI GALLINGANI, a subject of the King of Italy, and residing at Via Caffare 2, Genoa, Italy, have invented 5 certain new and useful Improvements in Hulls for Vessels in Armed Concrete, of which the following is a specification.

This invention relates to improvements in concrete ships' hulls, and the main object is 10 to provide a concrete hull which is of less weight than the concrete hulls heretofore used.

Another object of the invention is to provide a combined concrete and wood hull, 15 which is of simpler construction than the hulls heretofore known, and which is less liable to leakage.

With the foregoing objects outlined and with other objects in view, the invention consists in the novel features hereinafter described in connection with the accompanying drawing and more particularly pointed out 20 in the appended claims.

Referring to the drawing:

25 Figure 1 is a perspective view, partly in section, of the improved hull.

Fig. 2 is a detail sectional view taken on line A—A of Fig. 1.

Fig. 3 is a sectional view taken on line 30 B—B of Fig. 1.

Fig. 4 is a section on line C—C of Fig. 1.

In the drawing the hull comprises a concrete outer shell 1 reinforced by metal rods 2 and integral with longitudinal internal 35 frame beams 2^a and internal transverse frame ribs 2^b. The beams and ribs form pockets 2^c, which are lined with wooden planks 3 extending fore and aft and arranged closely adjacent each other trans- 40 versely of the ships, so that said planks when brought into contact with water will have a tendency to swell and cause their meeting side edges to form water-tight joints. The side edges of the planks 3 are provided with 45 undercuts 3^a, which have their greatest depth toward the inner surface of the planks, and the under-cuts of adjacent planks form dovetail recesses or grooves into which keys or projections 3^b of the shell 1 extend, so 50 that said shell is interlocked with the planks.

The outer faces of the planks are provided with dovetail grooves 4 which interlock with dovetail keys 4^a of the concrete shell. The ends of the planks are provided with dove- 55 tail grooves 4' with which the concrete of the

ribs 2^b are interlocked. The meeting edges of the planks may be provided with notch and tenon joints 5, if desired.

The wooden planks, though applied to the parts of the hull less subjected to strains, 60 contribute to the resistance of the structure and form elastic connections in either direction.

The improved hull, while possessing all the advantages of the ordinary concrete hull, 65 also has advantages not possessed by the ordinary concrete vessel.

An essential advantage of the hull according to the present invention resides in its small weight as compared with a hull entirely of armed concrete. With a hull according to the invention impermeability to water is assured, and in case the concrete shell cracks, the wood will absorb the small infiltrations and will swell, thus closing the 70 lining and preventing the water from entering the interior of the hull.

The hull of the present invention may be easily built, requiring only an exterior form for the shell and interior forms for the 80 beams and ribs, while the wooden planks 3, which form a part of the hull, assume themselves the function of the auxiliary lining for the interior of the shell.

The lining of wooden planks of the hull 85 also permits the gradual manufacture of the hull, as the wooden planks may be erected in accordance with the rapidity of the filling of the concrete. In this manner, the work 90 of construction may be interrupted without disadvantage. In employing wooden planks the exact arrangement of the iron rods with in the concrete is facilitated.

The lining of wooden planks will form the interior of the finished hull and the wooden 95 walls will offer greater facility in attaching the usual fittings required for the interior equipment. The wooden lining will also absorb shocks delivered to the interior of the hull.

The lining permits repairs to be made with great expediency and damaged interior elements may be speedily replaced without 100 damaging the concrete shell.

What I claim and desire to secure by Letters Patent is:

1. In a reinforced concrete vessel includ- 105 ing transverse frames of reinforced concrete, a lining of wooden planks extending fore and aft and having their side edges ar-

110

ranged closely adjacent each other, the ends of the planks extending into the transverse frames.

2. In a reinforced concrete vessel including transverse frames of reinforced concrete, a lining of wooden planks extending fore and aft and having their side edges arranged closely adjacent each other, the ends of the planks extending into the transverse frames, said planks being provided with grooves in which keys of concrete are arranged for interlocking the lining to the concrete vessel.

3. A vessel hull comprising a shell of reinforced concrete provided with interior

beams and transverse frames, a lining of wooden planks extending fore and aft and having their ends extending into the transverse frames, said lining being provided with grooves, and concrete keys integral 20 with said shell and interlocking with said grooves.

In testimony whereof I have signed my name to this specification in the presence of two subscribing witnesses.

LUIGI GALLINGANI.

Witnesses:

ADOLFO WEBER,

WILLIAM P. SHOCKLEY.
